UNITED STATES PATENT OFFICE.

WILLIAM R. BANKSON, OF PITTSBURGH, PENNSYLVANIA.

CONVEYER.

Application filed May 8, 1925. Serial No. 23,938.

This invention relates to conveyers, and the primary object of the invention is to provide a novel means adapted particularly for out-door use to transport articles or material from a point of supply to a point of deposit in an expeditious manner and at a minimum expense.

A further object of the invention is to provide a novel and improved conveyer of the gravity type in which a carrier is adapted to move down an inclined way, the device being so constructed as to permit the same to be controlled by a single attendant.

A still further object of the invention is to provide a gravity conveyer embodying a suspended track on which is mounted, for movement thereover, a wheeled carrier, and novel means including a single operating lever for changing the inclination of the track, whereby the wheeled carrier may be made to move from either end of the track to the other at the will of the operator.

Another object of the invention is the provision of a novel load carrier, and means to automatically effect dumping of its load upon reaching the point of deposit.

Still another object of the invention is to provide an improved gravity conveyer of the above kind which is extremely simple and durable in construction as well as efficient in operation.

With the above general objects in view, and others that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a side elevation of a gravity conveyer constructed in accordance with the present invention,

Figure 2 is a vertical transverse section of the device shown in Figure 1 drawn on a larger scale,

Figure 3 is an enlarged fragmentary side elevational view illustrating the load carrier and the means for effecting dumping of the contents thereof,

Figure 4 is a perspective view of the mounting bracket for the catch which holds the bottom door of the load carrier closed, and

Figure 5 is an elevational view of the catch.

Referring more in detail to the drawings, the present improved gravity conveyer embodies a track 10 upon which is mounted, for movement thereon, a carrier 11. The track 10 embodies a body portion having upstanding parallel marginal flanges 12 on which are adapted to travel the supporting wheels 14 of the carrier 11. Disposed at the longitudinal center of the track 10 is an upstanding attaching flange 15 to which are pivotally connected the lower ends of supporting links 16.

The carrier 11 consists of a hollow body or receptacle having a hinged bottom door 70 20 and in which the articles or material to be transported are or is placed, and this receptacle is supported by a hanger 21 which terminates in upwardly diverging arms 22 which carry the rollers 14 and 75 downwardly diverging arms 22^a which are attached to the sides of said body.

A pair of spaced longitudinal bars 25 are secured to suitable supports, such as the upper ends of posts 26 which are arranged in 80 two longitudinal series, and the bars 25 have aligned bearings 26^a in which the ends of transverse hanger rods 26^b are journaled, the latter having bell cranks 27 mounted thereon at their angles. The bell cranks 27 are preferably arranged in two series, one on each side of the transverse center of the device, and one series of the bell cranks are arranged in opposite relation to the other series, so 90 that arms thereof extend in opposite directions. As shown clearly in Figure 1, these oppositely extending arms of the bell cranks gradually increase in length toward the outermost bell crank for a purpose which will be hereinafter more fully described. 95 The extreme upper ends of the supporting links 16 are pivoted as at 28 to the ends of these arms of the bell cranks 27, and the other arms of the bell cranks 27 are all connected together by means of a rigid bar 100 29, so as to insure simultaneous movement of the bell cranks when the bar 29 is moved. The track 10 is thus arranged to swing in a vertical plane so as to change the angular position thereof relative to the horizontal, and it is thus obvious that the ends of the track will have a greater swinging movement than the center of the same, this is compensated for by the fact that the first above 105 mentioned arms of the bell cranks 27 decrease in length toward the innermost pair of bell cranks, as above stated.

Figure 4 is a perspective view of the mounting bracket for the catch which holds the bottom door of the load carrier closed, and

Figure 5 is an elevational view of the catch.

In order to change the inclination of the track, a hanger rod 31 is arranged at one end of the row of hanger rods 26^b, and this hanger rod 31 has mounted thereon, at a point intermediate its ends, the operating lever 32. The upper end of the lever 32 is pivoted to the bar 29 for effecting movement of the latter.

The bottom door 20 of the carrier 11 is held in closed position by the hooked lower end of a vertical pivoted catch 33 which is pivoted intermediate its ends to a pair of angular brackets 34 of the form clearly shown in Figure 4. The upper free end of the catch 33 is normally disposed in spaced relation to the end of the carrier 11, and is forced to this position by means of a spring 35 so that the catch 33 is normally in locking position for maintaining the door 20 closed. A suitable frame 36 is rigidly secured to and depends from the track 10 at the point of deposit, and this frame carries a bumper 37 which is disposed to be contacted by the upper end of the catch 33 when the carrier 11 arrives at the point of deposit, whereby the catch 33 will be forcibly released to automatically allow the bottom door 20 of the carrier to swing open for discharging or dumping the contents of said carrier.

In the use of the present device as shown in Figure 1, when it is desired to move the carrier 11 from the left hand end of the track to the other end, after the same has been loaded, it is merely necessary to swing the lever 32 to the left, or to the position shown, which will raise the left hand end of the track and lower the opposite end

thereof. The carrier 11 will now move down the track and thus transport the material carried thereby from one end to the other, and when the carrier arrives at the point of deposit, the upper end of the catch 33 strikes the bumper 37 so that said catch is swung for releasing the door 20, whereupon the contents of the carrier are immediately dumped upon the ground. When it is desired to return the carrier to its initial position for receiving a new load, it is merely necessary to swing the lever 32 to the right, which will change the inclination of the track by raising the right hand end thereof and lowering the left hand end of the same.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

In combination with a tilttable track and a bumper rigid with and depending from the track, a carrier mounted for movement on the track including a swingingly mounted bottom, a catch pivoted to the body for engagement with the bottom and with one end portion arranged to strike said bumper, and a leaf spring arranged between said portion and the body of the carrier.

In testimony whereof I affix my signature.

WILLIAM R. BANKSON.
